Primary Examiner—Louis S. Zarfas*Assistant Examiner*—G. Andoll*Attorney, Agent, or Firm*—Seed Intellectual Property Law Group, PLLC[57] **CLAIM**

The ornamental design for a stamp pad with articulated hinge, as shown and described.

DESCRIPTION

FIG. 1 is a front perspective view of a stamp pad with articulated hinge in accordance with an embodiment of my new design.

FIG. 2 is a front elevational view thereof.

FIG. 3 is top plan view thereof.

FIG. 4 is a bottom plan view thereof.

FIG. 5 is left side elevational view thereof.

FIG. 6 is a right side elevational view thereof; and,

FIG. 7 is a rear elevational view thereof.

The broken lines in the FIGURES are for illustrative purposes only and form no part of the claimed design.
